BATTERY BOX AND HANDLE

Filed May 21, 1927

HERBERT H. WYDOM,

By *John Middleton Donaldson & Hall*

Attorney

UNITED STATES PATENT OFFICE

HERBERT H. WYDOM, OF SOUTH BOSTON, MASSACHUSETTS, ASSIGNOR, BY MESNE ASSIGNMENTS, TO HOOD RUBBER COMPANY INC., OF WILMINGTON, DELAWARE, A CORPORATION OF DELAWARE

BATTERY BOX AND HANDLE

Application filed May 21, 1927. Serial No. 193,171.

The invention relates to battery boxes or containers of the molded composition type such as hard rubber or asphaltic compounds in which the battery cells are formed by integral partitions.

The invention aims to provide handle means for such containers which may be easily applied and removed, which when in position will be of ample strength to withhold the lifting and hold down stress, and in which the handle means will be capable of economical manufacture, and the method of connection will be such as to add nothing to the cost of the container over those customarily in use.

With these several objects in view the invention includes the novel features of construction and arrangement and combination of parts hereinafter described, the nature and scope of the invention being defined by the claims appended hereto.

An embodiment of the invention is illustrated in the accompanying drawing in which:

Figure 1 is a side elevation of the container with its handle means thereon.

Fig. 2 is a plan view.

Fig. 3 is an end view, and

Fig. 4 is a detail view of a modification.

Referring by reference characters to this drawing the numeral 1 designates the container, with its integral cell forming partitions 1a, which may be of the ordinary or any desired composition and construction except as hereinafter specified.

Each end wall of the container is provided with a thickened portion 1b extending transversely thereof which terminates at its upper edge in an abrupt shoulder b. Above this shoulder the said end wall is provided with a pair of abutments 1c between which is a handle loop receiving gap c, and the lower edges of these abutments being spaced from and opposed to the shoulder b, providing thereby the transverse grooves indicated at b1, the bottoms of which are in the same plane as the bottom of the gap c.

Each handle means or bail is made from a single piece of relatively stiff spring wire or rod of suitable metal and comprises a handle loop having a flattened or straight up-

per portion 2 and downwardly extending side portions 2a curved inward towards each other to form a narrow neck portion to fit the aforesaid gap c. Below the neck portion the handle member has two laterally extending portions 2b which lie in the above mentioned grooves b1.

At the corners of the container the ends of these groove entering portions are bent back at right angles to form side arms 2c embracing the sides of the container or box.

The ends of these arms are detachably pivoted to the side of the container, the axis of the pivots being parallel to the portions 2b.

A convenient form of detachable pivot may comprise cylindrical metal studs 3 secured to the side walls by screws 3a tapped into reinforcing inserts embedded in the walls of the box.

As an alternative the ends of the arms may be bent inward at right angles as indicated at 2a to engage recesses 1x formed in the sides of the box as shown in Fig. 4.

When the handle is to be applied to the box the ends of the arms are detachably engaged with the projections 3, or the recesses of Fig. 4, with the arms in inclined position as shown in dotted lines at the left of Fig. 1 at which time the portions 2b lie above the abutments 1c.

These have rounded or inclined upper edges c1. If now the handle loop is pressed down the inclines c1 will act as a cam and force the portions 2b outwardly until they ride over the abutments and drop into the grooves.

For removal it is only necessary to spring one of the arms outward until it clears the projection 3 (or recess 1x) and can be moved forward to the position shown in dotted lines on the right of Fig. 1, when the handle can be readily lifted off or completely disengaged.

Having thus described the invention, what is claimed as new is:

1. In combination in a battery container having side and end walls (enlargements on the end walls adjacent the top thereof, there being on each end wall an enlargement forming an upwardly facing shoulder and a pair of abutment enlargements above said shoulder and spaced apart therefrom to form a

groove, and from each other to form a space communicating with said groove, and a bail or handle member having an upstanding handle loop adapted to be disposed in said space between said abutments, said bail having portions extending laterally from said loop and lying in said groove, and having angularly turned hooked ends adapted to embrace the side walls of the container and pivot means on the side walls of the container adapted to be detachably engaged by the hooked ends of the said bail.

2. A container and handle according to claim 1 in which the said abutments are provided with inclined cam surfaces at their upper ends to produce a cam action on the groove engaging portions of the bail whereby the latter are pressed outward without spreading of the hooked ends, when the handle is swung down from an inclined position about its pivots to horizontal engaged position.

3. In combination, a container having upwardly and downwardly facing shoulder means thereon, a handle having a portion interposed between said upwardly and downwardly facing shoulder means and held against upward and downward displacement thereby, a bight in said handle, and shoulder means on the container and engaging the sides of the bight for preventing spreading of the handle.

4. In combination, a container having upwardly and downwardly facing shoulder means thereon, a handle interfitting with said upwardly and downwardly facing shoulder means and held against upward and downward displacement thereby, retention means on the sides of the container, said handle having side portions embracing the sides of the container and engaged with said retention means, a bight in said handle and shoulder means on the container and engaging the sides of the bight for preventing spreading of the handle.

45 5. In combination, a container having upward, also vertical and downward facing abutments, and metal handle means adapted to lie between said upward and downward facing abutments and between said vertical abutments and be held against upward, downward and sidewise movement thereby.

6. In combination, a container having side and end walls, upwardly and downwardly facing shoulder means on said end walls, a handle having a portion interposed between said upwardly and downwardly facing shoulder means and held against upward and downward displacement thereby, a bight in said handle, and shoulder means on the container and engaging the sides of the bight for preventing spreading of the handle.

65 7. In combination, a container having side and end walls, upwardly and downwardly facing shoulder means on said end walls, a handle interfitting with said upwardly and

downwardly facing shoulder means and held against upward and downward displacement thereby, retention means on the sides of the container, said handle having side portions embracing the sides of the container and engaged with said retention means, a bight in said handle and shoulder means on the container and engaging the sides of the bight for preventing spreading of the handle.

8. In combination, a container having side and end walls, upward, also vertical and downward facing abutments, on said end walls, and metal handle means adapted to lie between said upward and downward facing abutments and against said vertical abutments and be held against upward, downward and sidewise movement thereby.

9. Apparatus according to claim 7 in which said downwardly facing shoulder means are provided with inclined cam surfaces at their upper ends to produce a cam action on the shoulder engaging portions of the handle whereby the latter are pressed outward without spreading of the side portions when the handle is swung down from an inclined position about said retention means as pivots, in applying the handle to the container.

10. In combination, a container having side and end walls, upwardly and downwardly facing shoulder means on said end walls only, a handle interfitting with said upwardly and downwardly facing shoulder means and held against upward and downward displacement thereby, handle retention means on the sides of the container, said handle having side portions embracing the sides of the container and engaged with said retention means, a bight in said handle and laterally facing shoulder means on the end walls of the container and engaging the sides of the bight for preventing spreading of the handle, said side walls being substantially plain to permit the sides of the handle to move freely and unobstructedly over the side walls of the container in applying the handle thereto.

11. In combination, in a battery container having side and end walls, enlargements on the end walls only of the container and adjacent the top thereof, there being on each end wall an enlargement forming an upwardly facing shoulder and a pair of abutment enlargements above said shoulder and spaced apart therefrom to present downwardly facing shoulders forming a groove with said upwardly facing shoulder, and spaced apart from each other to present laterally facing shoulders forming a space communicating with said groove, and a bail or handle member adapted to interfit with said upwardly, downwardly and laterally facing shoulders and held against upward, downward and lateral displacement thereby, said handle having an upstanding handle loop adapted to be disposed in said space between said abutments

and having portions extending laterally from said loop and lying in said groove, and having hooked ends adapted to embrace the side walls of the container and pivot means on the side walls of the container adapted to be detachably engaged by the hooked ends of the said bail, said side walls being substantially plain to permit the sides of the handle to move freely over the side walls in applying the handle to the container.

10 In testimony whereof, I affix my signature.
HERBERT H. WYDOM.
